UNITED STATES PATENT OFFICE

WALTER G. HEGINBOTTOM, OF FLINT, MICHIGAN, ASSIGNOR TO MARVEL CARBURETER COMPANY, OF FLINT, MICHIGAN, A CORPORATION OF INDIANA

HEAT-CONTROLLING MEANS FOR CHARGE-FORMING DEVICES

Original application filed March 14, 1923, Serial No. 625,055. Patent No. 1,750,637. Divided and this application filed July 30, 1925. Serial No. 47,088.

This invention relates to certain new and useful improvements in heat controlling means for charge forming devices and is a divisional application of my application filed March 14, 1923, Serial Number 625,055, now Patent No. 1,750,637, the object being to provide novel means for controlling the application of heat to the charge forming device whereby the temperature of the charge can be regulated to a nicety in order to produce an explosive charge of high efficiency without any danger of overheating the charge throughout the entire range of operation of the engine under all atmospheric conditions.

Another object of my invention is to provide heat controlling means so constructed that when used in connection with an internal combustion engine that when starting the engine I am able to apply as large a volume of exhaust gases as desired for as long a time as desired to heat the charge, and so arranged that when the throttle is opened to any predetermined position from closed position to full open position, the means for controlling the application of heat will be operated so as to lessen the volume of the heating medium passing through the heating jacket.

A still further object of the invention is to provide means for allowing the charge throttling valve to move any predetermined desired distance before the exhaust throttling valve is moved, whereby the exhaust throttling valve will dwell on its seat while the throttle valve is moved a predetermined distance so as to hold the volume of exhaust gases in the heating chamber for heating the charge quickly while the engine is warming up.

A still further object of the invention is to provide an additional valve having a connection with the connecting rod of the exhaust and charge throttling valves so that the volume of exhaust gases delivered to the heat jacket will be regulated by the position of the exhaust valve.

Other and further objects and advantages of the invention will be hereinafter set forth

and the novel features thereof defined by the appended claims.

In the drawings,

Figure 1 is a side elevation of an internal combustion engine showing the application of my improved construction of heat controlling means thereto;

Figure 2 is a vertical section showing the valve in the exhaust gas intake of the heat jacket and its connection with the connecting rod of the throttling valve;

Figure 3 is a side elevation of my improved construction of heat controlling means; and

Figure 4 is a detail view of the guide member and its connection to the throttle and main exhaust valve.

In the drawing 1 indicates an internal combustion engine, 2 the exhaust manifold, 3 the intake manifold and 4 a charge forming device connected thereto which is herein shown provided with a valve controlled air inlet 5 to which is connected a conduit 6 extending from an air heater 7 located around the end of the exhaust manifold 2, said conduit being provided with an additional valve controlled air inlet 8 for regulating the temperature of the air delivered to the charge forming device.

The charge forming device 4 is provided with a heating jacket 9 having an inlet 10 which is disposed under an outlet 11 of the exhaust manifold 2 and secured thereto in any desired manner so that the exhaust gases from the exhaust manifold will circulate through the heat jacket 9 to heat the charge in its passage to the internal combustion engine and while I have shown a particular construction of heat jacket, it is, of course, understood that various forms of heat jackets can be employed without departing from the spirit of my invention and therefore I do not wish to limit myself to the particular manner of applying heat to the charge in its passage to the internal combustion engine.

The inlet 10 of the heat jacket 9 is provided with a valve 12 mounted on a stem 13 provided with an arm 14 for operating the same and is what I term a volume regu-

lating valve for controlling the volume of gases passing into the heat chamber of the jacket and is adapted to be operated in conjunction with the controlling mechanism as will be hereinafter fully described.

The end of the exhaust manifold 2 has mounted therein an exhaust throttling valve 15 carried by a valve stem 16 provided with an arm 17 for operating the same, said valve being capable of completely closing the outlet of said exhaust manifold to cause the entire volume of exhaust gases to pass through the heat jacket.

Secured to the end of the exhaust manifold 15 is a coupling 18 from which extends an exhaust pipe 19 to the muffler (not shown) in the usual manner. The coupling 18 is provided with an inlet nipple 20 from which extends a conduit 21 to an outlet nipple 22 formed on the heat jacket 9 of the charge forming device whereby the exhaust gases will be by-passed around the valve 15 when in closed position so as to pass through the heat jacket and heat the explosive charge in its passage to the internal combustion engine.

The charge forming device is provided with a throttle valve 23 carried by a shaft 24 provided with an arm 25 to which is connected an operating rod 26 controlled in the usual manner from the body of the vehicle to which the device is attached.

The main object of this invention is to control the application of heat to a nicely 35 so that the temperature of the charge being formed by the charge forming device can be controlled from the seat of the vehicle to which the device is attached in such a manner that after once being set, the application 40 of heat is controlled by the movement of the throttle valve of the charge forming device and to accomplish this result I arrange on the shaft 24 of the throttle valve 23 a cam 27, which is loosely 45 mounted thereon and is capable of turning on the shaft, the position of said cam being controlled by an operating rod 28 which is connected to a crank 29 provided with a lever 30 working in an indicating plate 31 secured to the dash of the motor vehicle as clearly shown in Figure 1, whereby the cam can be rotated around the throttle shaft.

In the drawing I have shown this cam mounted directly on the throttle shaft 24, 55 but it is, of course, understood that the cam can be mounted adjacent the throttle shaft on a suitable support and operated in the same manner, but I have found that the manner of mounting the cam is simplified by mounting it directly upon the shaft, but I do not wish to limit myself to any particular way and position of mounting the cam.

The cam is herein shown held in its adjusted position by frictional means which

comprises a pin 33 secured in the wall of the heat jacket and extending through a slot 34 formed in the cam plate 27, said pin carrying a frictional washer 35 held in frictional contact with the outer face 70 of the cam by coil spring 36 which allows the cam to be moved by the operating means located on the dash of the motor vehicle to which the device is attached and be retained in its adjusted position. 75

This is only one form of means for adjusting and holding the cam plate in its adjusted position and I do not wish to limit myself to the use of this particular 80 construction of means as I am aware that various other forms of means for adjusting and holding the cam plate in adjusted position can be used without departing from the spirit of my invention.

The cam plate is provided with a slot 85 37, the particular formation of which can be changed, but as herein shown it is provided at one end with a substantially vertical portion and a substantially horizontal portion, which gradually terminates 90 in a downwardly extending portion. Slidably mounted within the slot 37 of the cam plate is a member 38 provided with a roller having guide flanges for holding the same in the guide way formed by the slot and can be in the nature of an antifriction 95 roller to facilitate the movement of the member within the slot.

The member 38 is provided with a reduced outer end on which is pivotally mounted a hub 39 provided with a socket 40 in which is secured an operating rod 41 which has its free end pivotally and adjustably connected to the arm 17 of the exhaust gas 100 throttling valve 15. The member 38 carries a rigid arm 42 which is pivotally connected at its free end to a pin 44 pivotally mounted in the outer end of an arm 45 fixed on one end of the throttle shaft 24 whereby the member 38 travels vertically 105 in the vertical portion of the slot 37 of the cam plate when the throttle valve shaft is oscillated so as to allow the throttle valve to move a predetermined distance before the movement of the arm carried thereby causes the arm of the exhaust 110 throttle valve 15 to move, whereby the exhaust throttle valve 15 will dwell on its seat as the throttle valve opens until a predetermined distance has been reached where the further movement of the throttle valve will cause the exhaust valve to open or move therewith, the movement of the exhaust valve in respect to the throttle valve being 115 determined by the shape and position of the slot in the cam plate. While I have shown a slot of peculiar formation, I am aware that the same can be changed to increase or decrease the distance of travel 120 of the throttle valve before the exhaust 125 valve opens.

130

throttle valve is moved and therefore I do not wish to limit myself to the details of construction as herein shown as I am aware that various forms of cam plates can be used for guiding the member connecting the throttle valve to the exhaust throttle to cause the exhaust throttle valve to dwell on its seat a predetermined length of time after the throttle valve of the charge forming device has opened a predetermined distance.

In the construction shown and thus far described it will be seen that I have provided a heating means control wherein means is provided for completely diverting the exhaust gases out of their natural path of travel through a heating chamber to heat the charge in its passage to the internal combustion engine controlled by the movement of the throttle valve of the charge forming device in connection with adjustable means whereby the volume of exhaust gases delivered to the heating means can be controlled to a nicety so that under different atmospheric conditions more or less heat can be applied as necessary.

It will also be noted that in connection with the heating means for heating the charge produced in the charge forming device, I have provided an air heater which is located to the engine side of the exhaust throttle valve and so connected to the air inlet that the air will be heated before being delivered to the charge forming device, means being provided for regulating the temperature of the air by an atmospheric air valve.

For controlling the position of the volume valve I provide the operating rod 41 employed for a connection with the throttle valve of the charge forming device with a member 55 to which is adjustably connected a bolt 56 to which is pivotally connected an operating rod 57 which extends upwardly and is connected to the arm 14 carried by the shaft 13 of the volume valve 12 disposed in the inlet of the heating jacket so that it is moved with the exhaust throttling valve and by the adjustable connection, the relative positions of these two valves in respect to their closed positions can be changed and in practice I preferably connect the same in such a manner that when the exhaust throttle valve is closed, the valve 12 is wide open or vice versa and I have found that in this construction positive means is provided for completely cutting off the application of heat to the charge forming device by the movement of the throttle as when the throttle is moved into open position and the valve 12 is moved into closed position so as to completely close the exhaust inlet to the heating jacket of the charge forming device.

While in the drawing I have shown the volume valve arranged in the inlet passage

of the heating jacket for heating the explosive charge, it is, of course, understood that the same can be arranged in the outlet passage for controlling the volume of exhaust gases passing through said heating jacket as shown in my original application, Serial Number 625,055, filed March 14, 1923, now Patent No. 1,750,637, and therefore I do not wish to limit myself to the position of this volume valve for controlling the exhaust gases.

What I claim is:—

1. The combination with an internal combustion engine having an exhaust passage, intake passage and charge forming device connected thereto, of a heater for heating the charge in its passage to the engine, a valve for controlling the passage of exhaust gases to said heater, a valve for controlling the passage of explosive charge to said engine, an adjustable guide member, a movable member mounted in said guide member, a connection between said movable member and said valves, a volume valve for controlling the passage of exhaust gases through said heater, and a connection between said volume valve and the valve for controlling the exhaust gases.

2. The combination with an internal combustion engine having an exhaust passage, intake passage and charge forming device connected thereto, of a heater for heating the charge in its passage to the engine, a valve controlling the passage of exhaust gases to said heater, a valve for controlling the passage of explosive charge to said engine, an adjustable guide member, a movable member mounted in said guide member, means connecting said movable member to the valve for controlling the passage of explosive charge to said engine, a rod connecting said movable member to the exhaust controlling valve, a volume valve controlling the passage of exhaust gases through said heater, and a connection between said volume valve and said rod.

3. The combination with an internal combustion engine having an exhaust passage, intake passage and charge forming device connected thereto, of a heater for heating the charge in its passage to the engine, a valve for controlling the passage of exhaust gases through said exhaust passage, means for conveying the exhaust gases from said passage to said heater, a volume valve for controlling the passage of exhaust gases through said heater, a throttle valve for said charge forming device, a plate provided with a guideway disposed adjacent said charge forming device, a member mounted in said guideway and having a connection with the valve for throttling the exhaust and explosive charge, a connection between said exhaust throttling valve and said volume controlling valve and means for adjusting

the position of said plate to vary the effect of movement of the throttle valve on the exhaust throttling valve.

4. The combination with an internal combustion engine having an exhaust passage, intake passage and charge forming device connected thereto, of a heater for heating the charge in its passage to the internal combustion engine, a duct for supplying exhaust gases from said exhaust passage to said heater, a volume valve mounted in said duct, a valve in said exhaust passage, means for supplying warm air to said charge forming device, a throttle valve for said charge forming device, a member connecting said valves, means for guiding said member to vary the effect of movement of the throttle valve on the exhaust valve and a connection between the valve arranged in the duct and the valve in the exhaust passage.

5. The combination with an internal combustion engine having an exhaust passage, an intake passage and charge forming device connected thereto, of a heater for heating the charge in its passage to the engine, said heater being in communication with the exhaust passage, a throttle valve for said charge forming device, a throttle valve for said exhaust passage, a volume valve for controlling the passage of exhaust gases through said heater, an adjustable plate disposed adjacent the throttle valve of said charge forming device, a movable member mounted in said plate, a connection between said movable member and throttle valve of said charge forming device, a rod connecting said movable member with the exhaust throttling valve, adjustable means carried by said rod and a connection between said adjustable means and the volume valve.

6. The combination with an internal combustion engine having an exhaust passage, intake passage and charge forming device connected thereto, of a heater for heating the charge in its passage to the engine, a throttle valve for controlling the passage of exhaust gases through said exhaust passage, means for conveying the exhaust gases from said passage to said heater, a volume valve controlling the passage of exhaust gases through said heater, a throttle valve for said charge forming device, a plate provided with a guideway disposed adjacent said charge forming device, a member mounted in said guideway, a connection between said member and the throttle valve of said charge forming device, a rod connecting said member to the exhaust throttling valve, a block carried by said rod, a bolt adjustably mounted in said block, a rod connecting said bolt to the volume valve and means for adjusting the position of said plate to vary the effect of movement of the throttle valve on the exhaust throttling valve.

- 65 7. The combination with an internal com-

bustion engine having an exhaust passage, intake manifold and charge forming device connected thereto, of a heater for heating the charge in its passage to the engine, a valve for controlling the passage of exhaust gases to said heater, a volume valve for controlling the passage of exhaust gases to said heater, a valve for controlling the passage of explosive charge to said engine, a member having a connection with said valves, a connection between the exhaust throttling valve and said volume valve and means arranged in the path of travel of said member to vary the effect of movement of the charge throttling valve on the exhaust throttling valve.

8. The combination with an internal combustion engine having an exhaust passage, intake passage, a charge forming device connected thereto, of a heater for heating the charge in its passage to the internal combustion engine, a duct for supplying exhaust gases from said exhaust passage to said heater, a valve in said exhaust passage, a warm air stove for supplying warm air to said charge forming device, a throttle valve for said charge forming device, a volume valve controlling the passage of exhaust gases through said heater, a member connecting said volume valve to said exhaust throttling valve, a connection between said throttle valve and exhaust valve, means controlling the temperature of air delivered to said charge-forming device and means to vary the effect of movement of the throttle valve on the exhaust valve.

In testimony whereof I hereunto affix my signature.

WALTER G. HEGINBOTTOM.
